(57) **CLAIM**

The ornamental design for a body for television receiver, as shown and described.

DESCRIPTION

FIG. 1 is a front perspective view of the body for television receiver showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a back perspective view thereof;

FIG. 9 is a reference view showing the state of use that the display part has been attached horizontally and the caster has been attached at the bottom; and,

FIG. 10 is a reference view showing the state of use that the display part has been attached vertically and the caster has been attached at the bottom.

The broken lines depict portions of the body for television receiver that form no part of the claimed design.

The portions of the television receiver and castors shown in FIGS. 9 and 10 illustrate environmental structure and form no part of the claimed design.

1 Claim, 10 Drawing Sheets
